UNITED STATES PATENT OFFICE.

JAMES B. MORTON, OF MOREHEAD CITY, NORTH CAROLINA.

TROUSERS.

No. 916,577.

Specification of Letters Patent. Patented March 30, 1909.

Application filed October 8, 1906. Serial No. 337,994.

To all whom it may concern:

Be it known that I, JAMES B. MORTON, a citizen of the United States, residing at Morehead City, in the county of Carteret and 5 State of North Carolina, have invented a new and useful Trousers, of which the following is a specification.

This invention has relation to garments of the character indicated and it consists in the 10 novel construction and arrangement of its parts as hereinafter shown and described.

The object of the invention is to provide a pair or trousers with means for taking up or letting out the waist. Said means is located 15 directly above the pockets and the slack that is taken from the waist band is folded in at the pocket in such manner as to permit the garment to fit snugly about the waist of the wearer without bulging or puckering.

20 In the accompanying drawings:—Figure 1 is a view of a person having on a pair of trousers made in accordance with the present invention. Fig. 2 is a detail view looking at the outside of a garment waist portion, one of the lapping flaps being turned back to show the under parts; and Fig. 3 is a 25 top plan view of the garment.

The trousers 1 or similar garment is provided at its sides with openings 2, 2. The 30 waist portion of the garment at the openings in the sides thereof is formed with flaps 3 and 4. The flap 4 overlying the edge of the flap 3 preferably to a considerable extent. The outer flap 4 is preferably joined to the inner 35 flap 3 some distance below the upper edge of the waist portion of the trousers as at 5 so that there is considerable freedom of movement at the upper ends of the flaps. The pockets 6 are sewed at their edges to the flaps 40 3 and 4 in such manner that the said flaps constitute mouths for the said pockets. The eyes 7 are attached to the inner sides of the trousers at the waist thereof and the strips 8 are attached at their ends to the edges of the under 45 flaps 3, and pass through the eyes 7 then through the clasps 9 which are attached to the under sides of the flaps 4 and are adapted

to engage the buckles 10 which are attached to the outer side of the trousers at the waist thereof.

50 From the foregoing description it is obvious that the strips 8 may be let out in order to increase the diameter of the waist of the trousers or the said strips 8 may be drawn inwards in order to reduce the diameter of the waist and 55 trousers. It will also be observed that the slack that is taken from the waist is virtually folded into the pockets. Such a structure is admirably adapted for all sorts of trousers where it is not desired to use suspenders or 60 similar supports and especially where persons desire to go without a coat or outer garment.

Having described my invention what I 65 claim as new and desire to secure by Letters- Patent is:—

A garment comprising a front and a back separated by hip openings, flaps carried by the hip portions of the front and overlapping the hip portions of the back to close the hip 70 openings, pockets secured at their edges to the flaps and serving to receive the slack taken from the back, the flaps constituting the mouths of the pockets, loops secured to the hip portions of the front and concealed 75 behind the flaps, clasps secured to the inner sides of the front flaps adjacent to their rear edges thus to be concealed from view, and straps secured to the hip portions of the back and extending forward behind the flaps and 80 through the loops and then backward behind the flaps and through the clasps, the straps forming thereby closures for the pocket mouths, and means for attaching the free ends of the straps to the side portions of the 85 back.

In testimony that I claim the foregoing as my own, I have hereto affixed my signature in the presence of two witnesses.

JAMES B. MORTON.
